CLAIM

The ornamental design for a pixel display screen, as shown and described.

DESCRIPTION

FIG. 1 is a front perspective view of a pixel display screen showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view of the pixel display screen of FIGS. 1-8 in alternate configuration thereof.

The broken lines shown in the drawings depict portions of the pixel display screen that form no part of the claimed design.

1 Claim, 9 Drawing Sheets
